CALKING EQUIPMENT

Robert W. Thompson, Flushing, N. Y.

Application December 6, 1939, Serial No. 307,756

5 Claims. (Cl. 221—79)

The invention is an improved machine for filling calking-guns such as are used for applying calking composition to the junctions between masonry building walls and the metal trim for protecting the crevice against the entry of moisture, and for other filling purposes. Since on any given calking job there are many guns to be repeatedly filled, it is important that the machine used for that purpose shall operate quickly and easily and on a group of guns, and shall fill each solid with the calking paste without imprisoning air in the mass of paste inside the gun. Such air pockets in the paste greatly interfere with the work of calking since the air is under pressure and expands as it emerges from the gun nozzle, blowing the paste ahead of it so as to interrupt the continuity of the ribbon that is laid on the seam. For practical use such filling machines are required also to be easily transportable as from one job to another and hence to be light in weight and easily set up for use and easily filled with paste. The filling machine constituting this invention meets all these practical requirements in a high degree and affords an exceptionally rapid means of recharging calking guns.

The drawing illustrates the machine in its preferred form, Fig. 1 being a side elevation with parts in section, Fig. 2 a top plan with parts in section, Fig. 3 a cross section on line III—III of Fig. 1 and Fig. 4 a sectional detail of the press plunger.

The calking paste is placed in the cylindrical receptacle 1 which is also the base of the machine being adapted to rest by its bottom on the ground or floor and thereby provide a stable support for the machine, no supporting legs of any kind being used or desirable. The calking material as will be understood is an extremely sticky paste of about the consistency of soft putty. Being very viscous, it does not flow except extremely slowly. It is an important characteristic of this invention that the paste receptacle is wide enough, say not less than about 10 inches in diameter, which will not only provide a stable support on the ground or platform, as just stated, but also allow this sticky paste to be packed down solidly into it, as by the use of a trowel or the like. If it were of less diameter, it would be difficult if not impossible, to fill it without imprisoning air in the mass, because the troweling process necessarily requires a wiping action or cross-stroke for which there would not be room in a narrower receptacle. It will be understood

that if air is present in the paste in the receptacle it will later pass into the guns.

The receptacle 1 which thus serves as the base of the machine carries two opposite upright posts 2 and 3 welded to its sides and connected at their tops by a cross-head which is swivelled on the post 2 and removably engaged to the post 3. These posts are desirably hollow for the sake of lightness and are conveniently made by welding together the flange edges of two equal channel sections as indicated in Fig. 3. The swivelled joint is formed on the post 2 by welding in the upper end of one of the channels thereof a block 4 in which the pintle 5 is permanently fixed. The cross-head 7 swings on this pintle being confined thereon by the collars or nuts 6.

The other end of the cross-head 7, which is removably engaged to the other post 3, is for this purpose provided with an open-slotted end 8 adapted to hook under the head of a clamp bolt 9 screwed into a nut block 10 welded to one of the channels of the post 3. When the cross-head has been brought under clamp bolt 9 and the latter tightened, it becomes firmly secured in its operating position and when the bolt is loosened the cross-head and all of its carried parts can be swung bodily to one side and clear of the receptacle. This exposes the receptacle so that the difficult process of packing it with the paste is made as easy as possible. The clamp bolt is winged for easy manual operation.

The cross-head carries integrally at its center the nut 11 of a power screw 12 which is provided at its top with a handle or wheel by which it can be manually operated, and it is step-journalled at its foot in a press plunger 14, being rotatably confined to the latter in some suitable way sufficiently indicated in the present case by the set screw 13 in Fig. 1. The traverse of the screw in its nut 11 is sufficient to raise the plunger out of the receptacle so that it can then be carried to one side of the latter by the swinging cross-head away from post 3.

The press plunger 14 is composed in the present case, and preferably, of a body part (14) of wood bolted between upper and lower metallic facing plates 15 and 16 and braced by a top cleat 17 (Fig. 3) and it is provided around its periphery with a leather gasket 18 so designed and mounted as to be capable of easy entrance into the flared mouth of the receptacle to fit the latter snugly. It is further provided with as many sockets to receive the gun cylinders or barrels 20 as its available area will accommodate, and on both sides of the cross-head, such barrels normally

extending upwards above the cross-head. These sockets are marked 19. The parts of them that are in the bottom plate 16 are threaded to receive the threaded ends of the gun barrels. The parts of them that are in the wood body are slightly wider than the threaded parts and form soft-surfaced vestibules for the latter adapted to guide the threaded ends of the gun barrels, without marring them, into proper registry with the threaded holes so that the barrels, hastily thrust into these sockets, can be screwed home without risk of "crossing" the threads and thereby mutilating them. The vestibule parts of these sockets also form a desirable lateral support for the gun barrels to brace them against over-straining their threads from any lateral forces accidentally acting upon their upwardly extending ends. It will be apparent that by this construction the press plunger which is one of the pressure faces of the cylinder is adapted to have the gun barrels attached to it with great expedition and without any injury to the threads of either the guns or the machine under the rigors of practical use.

Because of the multiplicity of sockets and the unrestricted passageways formed by them, the power required for plunger operation is reduced to such extent as to bring the action within the range of light weight, easily portable and hand operated equipment. This advantage derives from the fact that lateral flow of the paste in the receptacle is minimized. The column of paste underlying each socket moves more or less bodily into the respective gun barrels attached thereto, and only such paste as underlies the spaces between sockets is required to flow laterally in order to reach and enter the socket. This is important since the viscosity of calking paste is such that if one or only a few sockets were provided the lateral flow thereto would require very strong and reinforced machinery to produce the required movement, thereby destroying the portability of the unit.

The gun barrels, it will be understood, are ordinarily about $2\frac{1}{4}$ in. in diameter and 3 or 4 feet long and, in the machine shown in the drawing, the plunger accommodates 20 of them. They are ordinarily pneumatically operated. When empty barrels have been screwed into all of the holes the operation of the hand wheel forces the plunger and all its barrels downwardly, into the receptacle, thereby extruding the calking paste in the receptacle upwardly into them. By first starting the plunger slightly downward so as partly to fill the threaded holes or sockets before inserting the gun barrels, it is easily possible to avoid trapping air within the barrels, that is to say, beneath the pistons 21 thereof (shown in dotted lines in Fig. 4) and such little amount of air as may inadvertently become caught will in any event be forced up to the top of the barrel as the upward extrusion progresses and will not be imprisoned in the mass of paste in the gun to produce trouble. The guns have applicator nozzles (not shown) which are screwed onto their threaded ends when they are filled and removed. These same threads are preferably used to attach the gun barrels in the plunger and in this connection it will be noted that when the barrels are screwed into the sockets there is no restriction to the passage of the paste into

the barrel, the socket outlet being as wide as the barrel.

As full barrels are taken from the plunger, empty ones can be inserted in their places and when a sufficient number of empties has been inserted they can be filled in the same manner by further advancing the plunger. However, as the power required to fill only one empty is excessive, the operator will not attempt advancing the plunger until a collection of them has been accumulated and inserted in the sockets, under which condition the plunger-screw, or hand wheel, may be easily operated.

The press plunger is desirably also provided with a pair of guide rods 22 rigidly bolted therein which slide in the bosses 24 of the cross-head and keep the plunger from turning with the screw and the barrels therein from striking the cross-head.

I claim:

1. A calking gun filling machine comprising, a calking paste receiving receptacle, a press plunger working in such receptacle, means to cause the plunger to exert pressure on the paste in such receptacle, one of the pressure faces in contact with the paste being formed with a plurality of sockets adapted for detachable connection to empty calking gun barrels, each barrel-receiving socket providing an unrestricted outlet for the paste into the barrel, of substantially barrel diameter, and being so close together that upon actuation of the plunger the relative movement of paste into the barrels is largely in the direction of the axes of the sockets and lateral paste flow within the receptacle is minimized.

2. A calking gun filling machine comprising, parts which in their assembly form a portable machine adapted to be moved about on the job and including a paste receiving receptacle of cylindrical form having a diameter adapting it to be filled solid with calking paste, said paste receiving cylinder being adapted to rest by its own bottom on the floor without legs or stabilizing bottom fasteners, a press plunger working in such receptacle, a screw for carrying said press plunger, a crosshead for supporting said screw, a post on said cylinder, said crosshead being mounted for swinging movement on said post, said press plunger being provided with gun barrel receiving sockets on both sides of said crosshead, each such barrel receiving socket providing an entrance for paste into the barrel attached thereto, which entrance is substantially of the same shape and cross area as the gun barrel connected thereto.

3. A calking-gun filling-machine as defined in claim 1 in which the barrel-receiving sockets are formed in the press plunger and extend upwardly therefrom.

4. A calking-gun filling-machine as defined in claim 1 in which the plunger is carried on a swinging cross-head and formed with the barrel-receiving sockets adapted to support such barrels extending upwards on both sides of such cross-head.

5. A calking-gun filling-machine as defined in claim 1 in which the gun-barrel-receiving sockets are vestibuled with soft material, like wood, adapted to avoid injury to the inserted barrels.

ROBERT W. THOMPSON.
